UNITED STATES PATENT OFFICE.

WALTER P. OSGOOD, OF MALDEN, MASSACHUSETTS, ASSIGNOR TO BOSTON MACHINE WORKS COMPANY, OF LYNN, MASSACHUSETTS, A CORPORATION OF MASSACHUSETTS.

STOP MECHANISM OF EMBOSsing AND LIKE MACHINES.

Application filed July 24, 1918. Serial No. 246,499.

To all whom it may concern:

Be it known that I, WALTER P. Osgood, a citizen of the United States, and resident of Malden, county of Middlesex, Commonwealth of Massachusetts, have invented an Improvement in Stop Mechanisms of Embossing and like Machines, of which the following description, in connection with the accompanying drawings, is a specification, 10 like characters on the drawings representing like parts in each of the several views.

This invention relates to stop mechanisms for disconnecting automatically the power drive in machines, and while having other 15 and more general fields of usefulness is well adapted and designed for use in embossing and like machines wherein a power operated presser ram or movable die is moved up to press the material against a relatively fixed 20 die. In machines of this kind it is desirable to have the connections of the movable ram under the control of the operator so that the ram may be either caused to dwell in position to press the material against the 25 fixed die, or be instantly withdrawn by a continuing movement of the driving mechanism after an operative impression according to the control by the operator as dictated by the requirements of the work in hand. 30 A prime object of the invention is to provide a simple and reliable mechanism preferably manually controlled as by a treadle device whereby the stop mechanism without other manipulation than the necessary 35 up and down movements of the treadle, is under the full control of the operator to impart ram movements that will either continue to press the material as long as desired, or instantly release the same and retract the ram, at will. To this end I provide a device that by a downward movement 40 of the treadle sets in motion the ram for a movement that if the treadle is at once released will result in a single complete cycle 45 of movement bringing the ram up into pressing contact with a fixed die and then withdraw it to initial position, but so constituted that if the treadle be held down instead of at once released, the ram will be 50 stopped midway of its cycle, i. e., while held in pressing contact with the material against the fixed die. The foregoing and other objects and advantages of the invention will more fully appear from the following de-

tailed description, and the distinctive features of novelty will be pointed out in the appended claims.

Referring to the drawings:

Fig. 1 is a side elevation with parts broken away showing a mechanism constructed 60 in accordance with my invention;

Fig. 2 is a plan view partly in section illustrating the essential feature of the invention; and

Fig. 3 is a transverse section on line 3—3 65 of Fig. 2.

The invention is herein illustratively shown as embodied in an embossing machine with a support structure 10 bearing at the upper portion thereof a relatively fixed die 11 and 70 co-operating mechanism, that forming no part of the present invention need not be further described herein, reference being had to my co-pending application Serial No. 247,777, filed August 1st, 1918 for a further 75 and more complete disclosure of such mechanism. Fitted for diagonal upward movement in the support structure is a presser ram or movable die 12 co-operative with the die 11 to form the impression or die mark 80 on the material. This ram 11 is shown as having a swinging link 13 connected to its upper portion for controlling the movement thereof, and with an adjusting device composed of the gearing 14 to determine the degree of pressing contact of the ram 12, these 85 features also constituting no part of the present invention. The ram 12 is operatively connected with a driving shaft 15 to be reciprocated by an eccentric 16 on said 90 shaft. The shaft 15 receives rotation from a driving wheel 17, this wheel being loosely mounted on a projecting end of said shaft and being intermittently clutched thereto 95 and disconnected therefrom by the stop mechanism now to be described. The hub 17^a of this wheel is equipped with a series shown as four in number of short projections 17^b constituting clutch abutments and adapted to be engaged by a sliding pin 18 100 fitted in a sleeve hub 19 fixed to the shaft 15 adjacent the wheel hub 17^a. The pin 18 is yieldingly pressed endwise to cause it to engage with the clutch projections 17^b by a spring 20 housed in the hub 19, and it has 105 a lateral projection or prong 21 through which it is controlled by cam or wedge pieces 22, 23 which are carried in spaced

2

apart relation on a yoke bar 24. The yoke bar 24 is slidably guided for limited horizontal movement on pins 25 set into the supporting frame, the yoke bar for this purpose having slotted ends 26 in which said pins are slidably fitted. The cam pieces 22, 23 are thus mounted oppositely with respect to the revolving movement of the projection 21, and they are so spaced with reference to 10 said projection, that when the bar 24 is moved to position either of them in the path of said projection, the other thereof will be out of the path of said projection as indicated with respect to the cam piece 22 in 15 dotted lines in Fig. 3. The bar 24 is controlled as to its sliding movement by a lever 27 which is pivoted to the pin 25 and formed at its inner end with an inclined slot 28 in which engages a pin 29 carried by the bar 24. The outer end of the lever 27 has pivoted thereto a rod 30 which may be connected with suitable manual operating means such as a treadle, and is normally held 20 at an upper limit of movement by suitable 25 constantly acting yielding means shown as a tension spring 31 anchored to the framework and engaged with said rod. Thus the bar 24 is normally held by the spring 31 in position so that the cam piece 23 will engage the finger 21 when it comes opposite thereto to withdraw the pin 18 and disconnect the shaft 15 from the driving wheel 17, this being the condition of rest. To operate 30 the machine the treadle rod 30 is depressed 35 thus moving the bar 24 to the right as seen in Fig. 3 and disengaging the cam piece 23 from the finger 21 thus permitting the pin 18 to move outward and the clutch to become operative. Thereupon the ram 12 receives 40 an operative movement which if the treadle is held down will terminate when the finger 21 comes against the cam piece 22 which will then be in position to engage the same,—thus stopping the ram while it is in 45 pressing engagement with the material against the fixed die 11. If however the treadle after being depressed is at once released the bar 24 will be again shifted to the left by the spring 31 before the finger 21 50 reaches the cam piece 22 and hence the shaft 15 will be permitted to make a complete revolution before the clutch is again thrown out by the cam piece 23 thus returning the ram to open position. For preventing too 55 free movement of the shaft 15, and insuring proper engagement of the clutch teeth, as well as the stopping of the shaft at the correct point without overthrow, the inner end of the shaft preferably has fixed thereto a brake disc 32 which is frictionally engaged by a brake shoe 33 adjustably held pressed thereagainst by a set screw 34 adjusted through a lug extending from the framework. In this way the operator is 60 enabled to cause the machine to operate either 65

for maintaining the ram in pressing engagement with the material as long as he may desire by merely holding down the treadle, or he may cause it to operate to press the material and then return by a continuous movement to open position, by pressing the treadle down and at once releasing it, thus giving him full control of the ram movements and without the introduction of any additional controlling devices or members whatsoever. The described means whereby the ram may be held in pressing engagement with the fixed die 11 as long as desired, is of special value and importance in an embossing machine of the general type wherein in the embossing or other impression is accomplished with the use of heat, as for example as shown in my prior Patent No. 1,252,299 patented January 1, 1918, since in this way the action of the heat may be utilized to a greater or less extent as conditions may require. While the invention is herein shown as embodied in an embossing machine it will be understood that the essential principles of the stop movement described are applicable to other uses not necessarily identical with this particular type of machine and I therefore desire the present embodiment to be considered in all respects as illustrative and not restrictive, reference being had to the appended claims rather than to the foregoing description to indicate the scope of the invention.

Having described my invention, what I claim as new and desire to secure by Letters Patent is:

1. Apparatus of the kind described, comprising power driving means, driven operative means, a clutch interposed between said driving means and driven means, and a stop motion for controlling said clutch having a manual governing device, said stop motion embodying spaced apart members with means for moving the same into and out of operative position with respect to said clutch, means for normally holding one of said members in operative position with the other of said members in inoperative position, said manual governing device having connections for moving the first named member to inoperative position, and the last named member to operative position, the last named member being located to engage the clutch to cause said driven means to stop midway of its cycle of movement, and the first named member being located so as to permit a full operative cycle of movement of said driven means.

2. Apparatus of the kind described, comprising a ram mounted for reciprocation into and away from an operative position, driving means therefor including a clutch connection, and a stop motion device embodying two spaced apart members mounted for movement to a position for engaging

selectively said clutch connection to render the same inoperative, means normally holding one of said members in operative position with the other of said members in inoperative position, and manually operated means for moving said members so that the first named member is in inoperative position, and the last named member is in operative position, the location of said members with respect to said clutch connection being such that when the first named member is in operative position, a full operative cycle of said ram is permitted, while when the last named member is in operative position, the ram is disconnected after a half cycle of movement.

3. Apparatus of the kind described comprising a driven member mounted for an operative cycle of movement, driving means therefor having a clutch connection to said driven member, and a stop motion for governing said clutch consisting in a projection mounted to rotate with a slideable element of said clutch and a treadle controlled shifter bar having opposite cam faces spaced apart 25 so that only one thereof will be engaged by said rotating projection when said treadle is released, so that a full operative movement of said driven member is permitted, the range of movement of said shifter bar being such that when said treadle is held depressed the second of said cam faces is in position to engage said projection to disconnect said clutch upon a partial rotation only thereof to cause said driven member to stop intermediate its cycle of movement.

In testimony whereof, I have signed my name to this specification.

WALTER P. OSGOOD.
